RACING GAME

Andrew H. Stewart, Shields, Pa.

Application April 17, 1937, Serial No. 137,554

7 Claims. (Cl. 194—6)

This invention pertains to a new and improved form of game or amusement device, and more particularly, to a traveling or racing device and/or to speed control thereof.

Previous to the present invention, machines and/or devices for amusement purposes have been based upon substantially similar mechanical features for their operative mechanisms, and for this reason, operate in substantially similar ways. As a result, they have lost much of their novelty and new devices working on the same mechanical principles do not create a new demand.

In view of the above situation, it has been an object of my invention to provide a new and improved type of device or game which will have great public appeal.

Another object of my invention has been to develop an amusement device employing new principles of operation.

A further object of my invention has been to devise a new method for controlling the speed of operation of racing or traveling amusement devices and/or to devise variable features of control that cannot be positively controlled by an operator.

A still further object has been to provide a race track device, the speed of operation of the elements of which may be variably controlled by an operator or operators, and/or such that a positive desired variation of speed cannot be obtained.

These and many other objects of my invention will appear to those skilled in the art from the illustrated embodiments of my invention shown, the description, and the appended claims.

In the drawings:

Figure 1 is a somewhat diagrammatical plan view of a preferred embodiment of my invention that is particularly suitable for indoor or miniature installations;

Figure 2A is a modified circuit arrangement which may be employed in connection with the arrangement of Figures 1 and 2;

Figure 2 is an electrical circuit arrangement of Figure 1;

Figure 3 is a horizontal view, partially in section, of an automatic, magnetically-controlled master switch, including a coin-operated switch mechanism;

Figure 4 is a vertical view in elevation of the coin-operated switch mechanism of Figure 3;

Figure 5 is an enlarged vertical detail of a feature of Figure 1;

Figures 6, 7, 8, and 9 are front plan views of various forms of control discs;

Figure 10 is a circuit diagram for a preferred method of operating a substantially full-size racing device adapted to have actual riders on the horses;

Figure 11 is a right side elevation of the head

of a horse having a speed control mechanism therein;

Figure 12 is a side perspective sectional detail of a preferred form of control mechanism;

5 Figure 13 is a vertical sectional detail showing a modification of the device of Figure 5.

In carrying out my invention, I preferably provide one or more electrically operated trucks upon which a horse or other racing device is 10 mounted. The movement of each truck about the track is controlled by a rheostat device, designed in such a manner that, after movement has been initiated, the truck will always move about the track at a certain minimum rate of speed until the requisite number of laps have been accomplished, and further, such that an operator may

15 vary the rheostat to increase the rate of travel of the truck. However, the preferred control is of a type such that a change of speed accomplished by a movement of the control arm of the rheostat cannot be definitely determined, and also, such that the change will be a variable one. This result is obtained by providing a rheostat disc which may be rotated at a desired speed; the disc is preferably of a segmental type having 20 odd-shaped segments or portions whose resistivity is different than adjacent portions. When a contact arm is manually moved over the face of such a disc during its rotation, it will be ap-

25 parent that the current supplied to a given truck will vary, and that the speed of such truck will thus be varied.

By providing a plurality of such mechanisms interconnected in a suitable manner, I have been able to devise a very interesting game which will 30 have a great public appeal, chiefly because each individual may have a race horse truck assigned to him, and because the change of speed of such horse above a certain minimum rate of travel can only be nonpositively controlled by him.

The invention may be employed in connection with miniature or indoor devices that will, of course, require a more complicated and intricate control circuit, and may also be successfully applied in connection with large size, or in effect, life-size devices which may be actually ridden by an individual. In the latter case, of course, the control system and/or circuit will be relatively simple. And, for the purpose of illustrating 45 my invention, I have shown in the drawings arrangements suitable for adaptation to both miniature and life-size installations.

As shown particularly in Figures 1-4, inclusive, I contemplate providing miniature or toy 50 size installations with a coin-operated switch mechanism, in order that revenue may be obtained, if desired, from the use of such device. Of course, if the device is to be used in the home, the coin slot mechanism may be eliminated 55 and/or suitably shaped conductor slugs may be

used. In the position shown in Figure 4, the metal coin C' bridges elements 24 and 25 to provide a closed circuit therethrough, see also Figure 2. As hereinafter set forth, this causes current energization of the holding coil 40.

Referring particularly to Figures 1 and 2, I have designated individual race trucks by the numerals 1a, 1b, and 1c, respectively. In Figure 5, I have shown a pedestal 2 extending upwardly from a truck 1 and having a suitable figure, such as a horse 3, mounted thereon. Of course, it will be apparent that any other figure such as an automobile, bicycle, motorcycle, airplane, etc., may be substituted without departing from the spirit and scope of the invention.

The truck 1 is provided with a pair of front wheels 6; a pair of back wheels 8 are directly driven by a motor 7 whose axial shaft is the axle shaft upon which the back wheels 8 are secured. The wheels 6 and 8 ride on a pair of suitably-shaped and spaced-apart track members 11; and, since one side of the motor is grounded to the frame-work of the truck, see the connection 12 of Figure 5, current connections are made to one side of the motor 7 through the tracks 11 and the wheels 6. Any other suitable form of truck and motor arrangement can be employed, if desired. The other connection between the electrical supply line and the motor is made through a third rail, spring-like slide contact member 9 which extends backwardly behind the truck 1 and slidably contacts a third rail 10.

The motors 7 of the trucks 1a, 1b, and 1c will be supplied with alternating or direct current through main or source terminals 50 and 51. Current control for each of the individual motors of the trucks 1a, 1b, and 1c, respectively, is accomplished by the circuits a, b, and c, respectively. An automatic make-and-break switch mechanism limits the operation of the motors 7 in such a manner that each one will stop after it has arrived at the finish line; and, when all of them have arrived at the finish line, such that the main circuit will be broken. The actuation of the motors can only be initiated again by inserting a coin in slot mechanism 21.

The slot mechanism 21 is shown particularly in Figures 3 and 4, as well as somewhat diagrammatically in Figures 1 and 2. A conductor coin, for example, a nickel, is inserted in the slot 21 and travels downwardly through a tortuous or twisting path, as indicated in Figure 4, until it completes an electrical circuit contact between a spring-like contact element 24 and a pivoted switch arm element 25. The guide chamber through which the coin moves is substantially centrally-twisted and cutout or slotted as shown, in order that a penny or other unsuitable coin of the wrong size will not reach the bottom or contact-making point. As soon as electrical contact is made between the elements 24 and 25, current from source 50-51 energizes a magnetic holding coil 40 of an automatic switch device D, see particularly Figures 1, 2, and 3. The actuation of the magnet coil 40 causes the switch D to close against compressive resistance presented by a spring 41, thus closing the magnet portions 32, causing electrical contact to be made between points 34 and 35 of an auxiliary magnet coil energizing live or circuit E (hereinafter fully explained), and also, causing contact to be made between points 36 and 37 of individual motor control circuits A, B, and C. In addition, electrical contact is made between points 45-46 through 75

a conductor strip on the bottom of switch arm 43 and through points 44.

The closing or down movement of the magnetic portions 32, as shown particularly by the dotted lines of Figure 3, causes the switch arm 43 to snap the switch arm element 25 about its pivot point 26 to release the coin and thus to break electrical contact. As shown in Figure 3, the pivoted arm element 25 is normally maintained in a switch-contacting relationship by a spring 49 that is secured to the arm at point 28 and to a stationary portion of the machine at a point 30.

The switch arm 43 is provided with a trip finger 47, that is pivotally mounted thereon by a pin 48, and that is normally held in alignment with the arm 43 by a tension spring 49. The spring 49 normally holds a tail portion of the trip 47 against a lug or pin 49a on the arm 43, but permits the trip to move against the tension of the spring 49 in the opposite direction when the automatic switch device returns to its original or open position, thus allowing it to pass the end of lever arm 25.

As shown in Figure 3, the automatic switch includes a central rod 39, a mount plate 38, and an upper switch contact-carrying insulated plate or arm element 31 having flexible connections 33 and separate-circuit switch-contact points 35 and 36. A magnetic shoulder portion 32 extends substantially centrally downwardly from the arm element 31 and is securely mounted on the pin 39. A similar shoulder 32 extends upwardly from the top of coil 40. When current flows through the magnetic field coil 40, the magnet portions 32 close and hold the switch contact portions in closed electrical contact with respect to each other.

The lower switch element or arm 43 is in like manner securely mounted on the shaft 39 and is provided with switch points 44 which contact with switch points 45 and 46. The spring 41 normally holds the switch contacts in an upper or open position except when the magnet coil 40 is actuated. The spring is positioned as shown between the lower face of the lower switch arm 43 and a bracket element 42. The rod 39 is slidably mounted with respect to coil 40 and carries switch elements 31 and 43.

It will appear that when the circuit represented by switch elements 24-25 is broken by the closing movement of the automatic switch coil 40, such coil will continue to be energized through an auxiliary line or circuit E which is connected to the coil through the contacts 34 and 35; thus, 40 is directly connected to terminal 50 and indirectly connected to terminal 51, through contacts 45-44-46, line 52, contacts 74, line E, and contacts 35-34, see particularly the circuit diagram of Figure 2. This circuit is connected in parallel with motor control switches A, B, and C, and is actuated through any one or all of these switches as long as electrical connection is made through one of these switches with the main supply line 51. However, when all of these switches have been opened, namely, when each of the devices has accomplished the requisite number of laps about the track, the circuit is broken and the coil 40 de-energized. This permits the spring 41 to break the contacts, 34-35, 36-37, and 44-45-46. To again initiate movement of the trucks 1a, 1b, and 1c, it is therefore necessary to insert a coin in the slot 21 and to move each truck 1a, 1b, and 1c to a position corresponding to that shown for truck 1c in Figure 1 of the drawings.

The individual control devices A, B, and C for the motor trucks 1a, 1b, and 1c, respectively, are automatic in action. Each truck is provided with an outwardly-extending side-trip-arm 14, see Figure 1, which strikes an adjacent finger of a three-segment or star wheel 15. The star wheel 15 is rotatably mounted and is provided with one slightly longer arm or segment that has a switch contact 16. The switch contact 16 is intermittently slid or moved along the inner circumferential face of a switch contact sleeve 17. The switch 16-17 is connected between one end of coil 70 and contact 74 of switches A, B, and C.

The star wheel 15 may be provided with two or more star or arm portions, corresponding to the number of laps about the track which are to be permitted. The three-element wheel provides three laps about the track. As shown, the trucks 1a, etc., will move three times around the track, each time contacting one segment of the wheel 15 and turning it; on the last lap, the switch contact portion 16 is moved from a righthand position (clockwise in Figure 1) to a lefthand position and the circuit between the points 16 and 17 will be broken, see Figure 2. This break is employed to, in effect, open the circuit between switch contacts 16 and 17 and to thus break the circuit to the corresponding holding coil 70 of the switches A, B, or C as the case may be. In the arrangement shown, the completion of the movement of a given truck about the track is represented by the positions of the arm 16 of the trucks 1a and 1b as shown in Figure 1 of the drawings. Truck 1c represents the new starting position. In other words, when it is desired to start the game after the finish of a race, each of the trucks is moved forwardly a sufficient distance such that the arm 16 will cause the switch contact 16 to move past the insulated snub or stop 18 into contact with the conductor sleeve 17. The snub or projection 18 may be of a suitable insulator material having sufficient flexibility to permit the contact point 16 to move therewith when the truck is again moved forwardly to a starting position. A spring-like insulated snub or projection 18 extends outwardly from the sleeve 17 and mechanically snubs the arm 16 when each truck arrives at the finish line; it is, of course, compressed when movement of the star wheel is again initiated.

The switch portions 16 and 17 make and break the holding coil actuating circuits of automatic switch or control devices A, B, and C. The magnetic motor control devices A, B, and C may be constructed along the lines of the main control device D, shown in Figure 3. Since each of these control devices is similarly connected and operates in the same manner, I will for the purpose of simplification, describe the operation of device A.

The motor control device A is connected to one side of the main current supply line 51 through a conductor 52. The magnetic switch includes a reciprocating rod 71, a magnetic holding coil 70, and a switch arm 72 that makes contact with switch points 73 and 74. The switch is normally held in an open position by a spring 76 mounted over the rod 71 and positioned between the arm 72 and a bracket 75. The arm 72, of course, is secured to the rod 71 and the rod 71 slides in coil 70 to cause the magnetic portions 32 referred to above to move into and out of contact with each other, or in electrical terminology, to "make and break" contact with each other. Any suitable standard form of magnetic switch may be employed such that conductor arm 72 may be moved towards and away from switch points 73 and 75

and 74. It will be understood that switches A, B, and C are not, in themselves, a part of the present invention.

Since, as before explained, each switch 16 and 17 is closed after the race has finished, the holding coil 70 of each control circuit device A, B, and C is immediately connected to the power line terminals 50 and 51 when the main control switch D is closed by the insertion of a nickel in the slot 21. The closing of switch D causes contact to be made between switch points 36-37, thus connecting the terminal 50 to one end of coils 70. The electric circuits of coils 70 of switches A, B, and C are simultaneously closed after the switch D has closed; all of these switches are held closed until each of the race trucks 1a, 1b, and 1c has completed three laps about the track and has arrived at the finish line.

Although the switch A is opened and stays open, when the truck 1a arrives at the finish line, the switch D will not be opened until the switches B and C have been opened in the same manner. Thus, each truck 1a, 1b, and 1c will arrive at the finish line before the current is shut off to its motor 7a, 7b, and 7c, respectively, and all must arrive before the current is shut off to the magnet coil 40 of main control switch D.

When the circuit through contacts 16-17 is broken by the truck 1c reaching the last lap, the coil 70 of switch C is de-energized and the spring 76 returns the switch to an open position breaking the circuit at 73-74, and thus, breaking connection between the motor 7c and the power line terminal 51. Of course, after all the switches 16-17 have opened and then again been closed, the switches A, B, and C will remain open, since the holding coil 40 of switch D will be disconnected with respect to terminal 51 when the switches A, B, and C have opened, thus, breaking connection between line E and point 46 of switch D. Since the energization of the magnetic coil 40 of the main control switch is dependent upon current supply from the terminal 51 and at least one of the switches A, B, and C, it will be apparent that when all of the contacts 73-74 have been broken, no flow will be accomplished to the connection 35 and the coil 40 will be de-energized, permitting the switch to open.

The speed control of each of the motors 7a, 7b, and 7c of the trucks 1a, 1b, and 1c, respectively, is accomplished by the circuits a, b, and c, respectively, which are in parallel with respect to each other. Each circuit includes a resistance 53 in parallel with a variable resistance 54. The resistance 53 is of a high value and represents the minimum slow rate of travel of a given truck about the track. However, the rate of travel of the truck may be varied by the resistance 54 in that a decreasing of its resistance below the resistance of 53 will cause the majority of the current to pass through the circuit 54, and to thus, detour around the circuit 53.

As shown particularly in Figures 1 and 12, the rheostat control mechanism includes a disc 54, a radially movable manual control arm 60, a control arm contact element 59, and a spring 61 which normally holds the contact 59 centrally of the disc 54 in contact with a central contact spot 56 which is connected to the parallel circuit a, b, or c, see Figures 6 to 9, inclusive. As shown particularly in Figures 1, 11, and 12, the rheostat disc 54 is secured for rotation on the shaft 62, preferably removably secured as by keying or screw-threading it with respect to the shaft. As shown particularly in Figure 12,

the disc 54 is provided with a mount portion *h* which is directly secured to the end of the shaft 62 and a rheostat portion *i* that is insulated from and securely mounted on the portion *h*. The portion *h* is preferably of some suitable insulating material such as Bakelite, etc. A controlling handle or knob *j* is adapted to slide within a suitable guide *k* and to thus move the contact 59 substantially radially across the face of the rheostat portion *i* of the disc 54 against the tension of spring 61. An annular contact surface 57 is mounted on the shaft 62 and slidably contacts with a brush 88 connected to the current supply terminal 50, see Figure 2, through rheostat 67 and motor 66. The shaft 62 and the contact 57 of the disc 54 are revolved through the agency of a pulley wheel 63, a drive belt or chain 64, a pulley 65 and a motor 66. The motor 66 is connected in the line 58 and its speed is controlled by rheostat 67. As shown, the motor is preferably connected in such a manner that it may drive the discs for each of the circuits *a*, *b*, and *c*. Each disc may be provided with separate drive mechanisms if desired.

Since the various portions or segments of the resistance discs 54, see particularly Figures 6-9, inclusive, are of different resistivity, a slide movement of the contact element 59 to the right of Figure 12, causes different portions of the disc to contact with the contact element 59 and to decrease and increase the current flow in the circuit. That is, the contact element 59 is moved substantially radially of the disc 54 by the operating arm 60. The change of speed will depend upon the shape of the segments and the type of materials employed in making them. In Figure 9, I have shown a rheostat or potentiometer type of winding on each of the segments. Of course, this type of disc will have a greater speed range than a metal piece type. Various ranges of speed may be obtained by using metals of different resistivity, such as iron, copper, aluminum, brass, nickel, etc., and various alloys.

In operation, a nickel or other conductor coin is inserted in the slot 21, contact is made between the switch points 24 and 25 causing an actuation of switch closing coil 40 of main switch D. The magnetic coil 40 immediately closes the main circuits connecting them to terminals 50-51 and causes the trucks 1a, 1b, and 1c to move after the individual control switches A, B, and C have been energized and closed.

The rate of travel of each of the trucks will be varied by the rheostat control circuits *a*, *b*, and *c*, which are in turn, at least indirectly controlled by the speed of the motor 66. After the requisite number of laps have been accomplished, each of the switches A, B, and C is automatically opened and the main circuit of the switch D is finally automatically broken after all the trucks have reached the finish line. After the main control switch D has opened, a new coin must be inserted to initiate further operation. It should be noted that the coin switch circuit represented by switch elements 24-25 is immediately opened by the operation of the main switch D whereupon the coil 40 of the switch D is energized through an auxiliary line or circuit E which is in turn controlled by the individual motor control devices or magnetic switches A, B, and C. Since none of the holding coil circuits is energized except after a coin has been inserted, no current is used when the device is idle.

From the above description, it appears that the operation of the device is entirely foolproof

and is relatively simple as far as the individual operators are concerned. If the device is to be employed in life size and the operators are to sit on the horses 3, a circuit such as shown in Figure 10 may be successfully employed. This is a simplification of the circuit shown in Figures 1 and 2. Each of the motors 7 is controlled by circuits *a'*, *b'*, and *c'*, which are connected in parallel to the supply terminals 50 and 51. The operation of the trucks may be stopped and started by a master switch 89 operated by the attendant; and, the maximum rate of travel and the starting of the horses can be controlled by a master control rheostat 90. The rider of each horse 3 can thus only non-positively control his speed of travel.

In this layout, it is preferable to mount the disc operating motor 66' in the head of each horse. Thus, the operator can control the rheostat through the reins 4, see Figure 11. As shown, the reins 4 are connected to a pull arm 30 which extends through a slot in the face of the horse, and which, as shown particularly in Figures 11 and 12, is connected to a slide contact element 59. The contact 59 is the element 59 shown in detail in the embodiment of Figures 1 and 2 and is normally maintained in a neutral position, corresponding to the axial center of the disc 54, by the tension of a spring 61 which is pivotally connected to the slide contact element 59 and to a mount lug 85.

Although there are many novel features involved in the present invention, it will be apparent that the speed control which is non-positive as far as the individual operator is concerned, is one of the important features thereof, and as shown in Figure 13, is applicable to a mechanism operated by any suitable actuating means, although of course it will be apparent that electrical means will provide relative simplicity of control and will perhaps be more practical.

As shown particularly in Figures 2 and 2A, I also contemplate providing, if desirable, an individual push button switch mechanism for controlling the start of each motor truck 1a, 1b, and 1c. The push button switch connection may be made between the terminals *e* and *f* in each of the motor control circuits *a*, *b*, and *c*. The switch itself is simple in construction and includes contact points *g* and *h* and a magnetic holding coil *i* which is energized as long as the respective motor circuit is energized. Thus, an individual operator can press in the button at the start of the race and the coil *i* will hold the button in a closed position to the end of the race or until the motor circuit has been broken by the release of the magnetic switch A, B, or C, as the case may be.

I have employed an individual coin mechanism for each of the actuating circuits of the motor driven trucks 1a, 1b, and 1c. However, I have shown a single slot control switch in the illustrated embodiment of my invention.

It will appear that the rotation of disc 54 effects what may be termed a cyclic change of resistance, and thus, of speed of the associated truck motor; a variation of the motor drive control resistance 67 can thus be employed to effect a change in the frequency of the above-mentioned cyclic variations.

In the embodiment of Figure 13, I have shown a pair of speed-reduction gears that are driven from the motor 7. This gear train actuates a 75 rocker cam mechanism which is pivotally con-

nected to a pivotally mounted horse 3', in order that actual riding conditions may be assimilated by the rocking of the horse as the truck 1 moves about the track 11.

It will be apparent that many other circuit and operating arrangements may be employed in connection with my invention and that the circuits and arrangements shown are merely illustrative. Voltage and/or current actuated holding coils may be employed in connection with the switch circuits. In the outdoor device, the speed control mechanism may be operated by a knob, by the stirrups, or in any other suitable manner; each horse may also be provided with a stop and start control, if desired. Also, proper mechanical elements may be employed for actuating the horses' legs, if desired.

From the above illustrations and applications of my invention, it will appear to those skilled in the art that many other modifications, substitutions, additions, and/or combinations thereof may be made in connection with the present disclosure without departing from the spirit and scope of my invention as indicated in the appended claims.

I claim:

1. In an amusement device, at least two movable trucks, a motor for actuating each of said trucks, a source of power, a coin-controlled switch mechanism connected between said motors and said source of power, means for holding said coin-controlled switch mechanism in a closed position, and additional switches connected between said motors and said first-mentioned switch, said additional switches being connected to release said holding means and open said first-mentioned switch mechanism only after all of them have been opened by a predetermined movement of each of said pair of trucks.

2. In an amusement apparatus, a pair of tracks, a truck operably mounted on each of said tracks and adapted to move thereon, a source of power, actuating means operably associated with each of said trucks, connections between said source of power and said actuating means, and rheostat means interposed between said source of power and each of said actuating means for automatically controlling the rate of movement of the trucks about their associated tracks, and means operably associated with said rheostat means for impositively controlling the rate of movement of said trucks during their automatic control by said rheostat means.

3. In an amusement apparatus, at least a pair of tracks, at least a pair of trucks movably mounted on said tracks, a motor drivingly connected to each of said trucks, a source of energy for energizing said motors, means automatically operated after said trucks have completed a predetermined number of laps for cutting off the supply of energy to each of said motors when each of said trucks approaches a line transverse to the movement of said trucks and representing a finish line, and means connected between said source of energy and said motors for cutting off the supply of energy to both of said motors only after both of said trucks have reached the finish line.

4. In an amusement apparatus, a pair of tracks, a truck operably mounted on each of said tracks and adapted to move thereon, a source of power, an actuating means operably associated with each

of said trucks, connections between said source of power and said actuating means, a normally-closed trip means operably associated with each of said actuating means and connected between

5 said actuating means and said source of power, said trip means being adapted to be opened for cutting off the supply of power to each of said actuating means after a predetermined number of laps of said trucks about said tracks, means operably connected between said source of power and said trip means for preventing a restarting of another race after one truck has been stopped at a finish line by the opening of said trip means, and after said trip means has again been closed, 10 until all of said trucks have reached a line extending transversely of the movement of said trucks and designated as the finish line.

5. In an amusement apparatus, at least two movable trucks, a motor for actuating each of 20 said trucks, a source of power, a primary switch mechanism operably connected between said motors and said source of power, secondary switches connected between said motors and said primary switch, said primary switch having a coil for holding it in a suitable position, said secondary switches being operably connected through switch points to said source of power and said holding coil, and being constructed, arranged, and connected to cut off energization of said holding 25 coil to thereby open said primary switch only after all of said secondary switches have been opened by a predetermined movement of each of 30 said pair of trucks.

6. In an amusement apparatus, a track, a plurality of amusement mechanisms adapted to move about said track, a source of energy for said amusement mechanisms, an automatic switch having contact elements connected to said source, means for closing said switch, means for holding

40 said switch closed until said automatic switch is actuated by said source of energy, said thus-actuated automatic switch being adapted to operably connect said source of energy to said amusement mechanisms, means operably associated 45 with and actuated upon actuation of said automatic switch for releasing said switch holding means, and means operably connected between said automatic switch and said amusement mechanisms for automatically opening said automatic 50 switch when all of said mechanisms have moved about said track a predetermined number of times.

7. In an amusement device, a source of power, movement-producing mechanisms, a switch connected to said source of power and connecting one side of said source of power to said movement-producing mechanisms, additional switches, one for each of said movement-producing mechanisms, said first-mentioned switch connecting

55 another side of said source of power to said additional switches, each of said additional switches being connected to an associated movement-producing mechanism, means associated with said first-mentioned switch for closing it and closing 60 said additional switches, means associated with each of said movement-producing mechanisms for opening its associated additional switch, and means effective for opening said first-mentioned 65 switch only after all of said additional switches have opened.

ANDREW H. STEWART.
